UNITED STATES PATENT OFFICE.

FRANK D. MOSES, OF TRENTON, NEW JERSEY.

GAS-GENERATING APPARATUS.

1,378,125.

Specification of Letters Patent. Patented May 17, 1921.

Application filed August 8, 1919. Serial No. 316,240.

To all whom it may concern:

Be it known that I, FRANK D. MOSES, a citizen of the United States, residing at Trenton, county of Mercer, State of New Jersey, have invented a certain new and useful Improvement in Gas-Generating Apparatus, and declare the following to be a full, clear, and exact description of the same, such as will enable others skilled in the art to 10 which it pertains to make and use the same, reference being had to the accompanying drawings, which form a part of this specification.

This invention relates to gas generating 15 apparatus, and the general object of the invention is to provide a construction of a water gas generating set and a boiler-superheater construction in which the heat developed by the successive blasts of the generator may be utilized in the generation of 20 steam and super-heating thereof nearly to a point of disassociation of its elements prior to contact with the fuel bed.

In the manufacture of water-gas both the 25 blast gas and the manufactured gases leave the apparatus at a high temperature, thereby carrying with them a large amount of sensible heat that, if utilized in the production of steam, would generate a sufficient 30 quantity of steam for the purpose of water-gas manufacture thus conserving the boiler fuel now employed in the usual apparatus for this purpose. Numerous attempts have been made to accomplish this result which 35 have heretofore met with little success due to the fact that the gases are produced at intermittent intervals, and that the temperature thereof fluctuates from about 800 degrees F. to about 2500 degrees F. during the 40 production and further, that the demand for steam in such apparatus arises at a time when the heat for its production is not available, therefore requiring excessively large boilers and producing internal strains that 45 render the boilers unsafe and subject to constant inspection and repair.

An object of my invention is to provide 50 boilers that will utilize the waste heat under the described conditions and of a construction that will not be subjected to undesirable strains arising from such conditions. A further object is to provide a novel means and method of super-heating steam prior to its application for the manufacture of gas 55 or for other purposes. The invention fur-

ther consists in the several novel features of construction of boiler-superheaters and the arrangement of the several parts of a gas generating set as is hereinafter more fully described and claimed. A form of construction and arrangement of parts involving my invention is shown in the accompanying drawings in which—

Figure 1 is a cross section of a gas generating set embodying my invention.

Fig. 2 is a plan view thereof.

Fig. 3 is a detail in section of two boiler tubes and portion of the tube head showing the manner of protecting the same by the use of refractory material.

Fig. 4 is a detail in section of part of the heat absorbing refractory material used in conserving heat.

In my improved apparatus I employ an ordinary generator 1 in which the combustible material as coal, coke, charcoal or the like is placed, and on one side of this generator is what I have termed a boiler-superheater 2 through which the blast gas passes, and on the opposite side is a somewhat similar boiler 3 through which the manufactured gas passes to the line to a storage tank.

As before stated, the generator is of the ordinary type having the usual grate 5 near the bottom to support the fuel bed. A conduit 6 leads from the boiler-superheater 2 to below the fuel bed in which conduit is a valve 7, and a conduit 8 leads from beneath the grate to the bottom of the boiler 3. This conduit 8 is also provided with a valve 9 for closing the same to the bottom of the generator. The generator is provided with the usual fuel door 10 and at the upper end is provided a conduit 11 leading into the conduit 6 between the valve 7 and the boiler-superheater 2. This conduit 11 is provided with a valve 12 by means of which it may be closed and a vent pipe 13 is provided in the conduit 11 between the valve 12 and the top of the generator. A conduit 14 leads from the top of the generator to the conduit 8 between the valve 9 in the said conduit and the boiler 3. This conduit 14 is also provided with a shut-off valve 15. The vent 13 is provided with a valve 16 at the top, and the boiler 3 is provided with a similar valve 17 at the top.

The boiler-superheater 2 consists of an outer shell 18 providing a water and steam chamber closed at the top by a header 19.

An inner or fire shell 20 is provided open at the lower end to the conduit 6 and air is introduced into the bottom of the inner shell 20 by means of a valved conduit 21. A similar 5 conduit 22 leads into the bottom of the generator below the grate and both the conduits 21 and 22 are provided with similar valves 23 and 24 respectively for controlling the air flow and both the conduits are connected 10 with a common supply conduit 25.

The upper end 26 of the shell 20 provides a header for the vertical tubes 27 extending from the header 26 to the header 19 through which gases of combustion may pass when 15 the valve 17 is open. As a protection for the tubes I provide the inside of the header with a shield 28 of refractory material and the lower ends of the tubes are also provided with refractory material 29 extending into 20 the tubes for a short distance which completely covers the ends of the tube head as will be understood from the detail Fig. 3. I also provide a heat absorbing element within 25 the fire shell 20 which consists of a "checker-work" 30 preferably formed of rows of bricks of refractory material, one series of rows extending preferably at a right angle to the two adjacent series and practically the entire shell is filled with these superimposed 30 rows of bricks, the purpose of which is more fully described hereinafter.

The chamber 31 between the shell 18 and 20 and about the tubes 27 is the water and steam space of the boiler. A valved water 35 inlet is provided at the bottom of the shell 18, and a steam outlet is provided about the top of the shell 18 beneath the header 19. To the steam outlet 33 is connected a steam pipe 34, having a valve 35, which enters the 40 top of the fire chamber just beneath the tube head 26.

The boiler 3 is used to cool the generated gases and to conserve the heat of the said gases and is similar in construction to the 45 superheater 2. The boiler 3 consists of the outer shell 36, the inner or fire shell 37 and a series of tubes 38 extend from the upper end of the fire shell 37 to a header 40 above which is a chamber 41 from which the gas 50 passes through the conduit 42 to the seal 4. The shell 37 is provided with a valved water inlet 43 at the bottom and a valved steam outlet 44, and this steam outlet may be connected, if desired, with the steam conduits 55 of the boiler-super heater 2. For convenience, it may be directly connected with the pipe 33 as indicated at the left of Fig. 1, a portion only of the pipe 44 being shown.

In operation the fire is started in the generator which, as heretofore stated, is filled 60 with a combustible material. To bring the fuel bed in the generator to a state of incandescence, air under pressure is admitted through the valve 24 and tube 22 which 65 opens beneath the grate of the generator as

indicated at 45 in Fig. 1. At this time the vent valve 17 of the boiler-superheater 2 is open and the valve 16 closed and the valves 7, 9 and 15 are closed and the valve 12 is open. The products of combustion pass 70 through the conduit 11 and the "checker-work" 30 of the superheater 2 and through the vent controlled by the valve 17. In this operation carbon mon-oxid (CO) is usually present in the products of combustion and to 75 conserve this, as well as the sensible heat of the combustion gases, air is admitted through the valve 23 and through the opening 46 beneath the "checker-work" for the purpose of burning the CO. During this operation, which lasts about four minutes, the blast gases reach the "checker-work" or brick at about 800 degrees F. at the beginning of the blast and increase in temperature to about 2500 degrees F. at its end. For the 80 purpose of conserving this heat, I have employed the "checker-work" described and with refractory material covering the tube head and extending into the tubes a short distance. By positioning the "checker-work" 90 before the tube head through which the blast gases must necessarily pass, the heat is absorbed and the temperature reduced to a considerable extent before the gas reaches the tubes, and the tubes are not subjected to excessive fluctuations of temperature as would otherwise exist. Furthermore, the heat absorbed by the checker brick in this manner will be later transmitted to the boiler proper during the period between blasts when steam 95 is required for gas generation.

After the gas making apparatus has become properly heated the air valves 23 and 24 are closed, the valve 17 is closed and the valve 7 is opened and the valve 9 closed. 105 Thereafter, the steam produced by the heating of the boiler 2 is admitted through the valve 35 and passes down through the hot fire brick or "checker-work" 30 and becomes intensely heated nearly to the temperature 110 at which it will disassociate and combine with the carbon of the fuel bed when it comes in contact therewith. In this case the oxygen of the steam (H_2O) combines with the carbon (C) of the fuel bed forming carbon dioxide (CO_2) at first and releasing the hydrogen (H_2). The resulting gases then pass through the zones of the generator indicated at I and J where the carbon dioxide (CO_2) takes up carbon and becomes carbon-mon-oxid (CO) and passes out through the valve 15 to the boiler 3. This gas has a temperature from 800 to 1400 degrees F. and in passing through the "checker-work" 115 in the fire shell 37 the said "checker-work" absorbs the heat from the gas reducing its temperature prior to contact with the tubes 38. The cooled gas passes into the chamber 41 and thence through the tube 42 to the seal chamber 4. This "run" or gas making 120 125 130

period of the apparatus continues for a period of several minutes. At the end of this period the "checker-work" in the boiler 3 has been heated up to approximately 1400 degrees F., and this heat is gradually given off, between the "runs" to the boiler above and surrounding this "checker-work." At the beginning of the next run the gas entering the boiler 3 at a temperature of about 800 degrees F. absorbs some of the heat of the "checker-work" which is conducted by means of the tubes to the water of the boiler. A comparatively even temperature is thus maintained in the boiler 3. This "checker-work" or fire brick utilized in boilers or superheaters 2 and 3 has the function of taking up part of the heat and reducing the temperature of the gases of combustion or the generated gas as the case may be and the quantity of the fire brick forming the "checker-work" provides a sufficient body to maintain the boiler under nearly constant temperature throughout the period of operation. The sensible heat of the gases is consequently conserved and utilized and thus, during the periods in which no gases of combustion for instance are passing through the boiler-superheater 2, the intensely heated fire brick of the "checker-work" serves to maintain the temperature of the boiler while the gas making "run" occurs. The "checker-work" also in case of the boiler-superheater 2 serves to prevent the flame of the blast from impinging directly against the tube head and avoids the disastrous results of intermittent heating and cooling.

By the use of the boiler-superheater described, longer and better runs can be made as the steam is superheated for both the "up" and "down" runs by using the valves 7, 9, 12 and 15. The apparatus increases the production of gas as the steam is heated nearly to the point of disassociation upon contacting the fuel bed. In apparatus heretofore used, saturated steam entering the fuel bed has to be brought to the temperature of disassociation within the bed, which requires the utilization of practically one-fourth the fuel bed before CO_2 is formed, and this takes up the carbon and becomes carbon mon-oxid (CO) in passing through the last zone. By the apparatus described the reaction to carbon dioxid (CO_2) takes place immediately upon the steam contacting the fuel bed.

The valve 16 heretofore mentioned in the upright flue 13 is an emergency valve and should, for any reason, the boiler superheater 2 be out of commission, the apparatus could be operated by using the valve 16 and cutting out the boiler super-heater by closing the valve 12.

It is evident from the operation described

that the apparatus could, with slight modification and by use of another boiler superheater similar to the super-heater 2, be used to pre-heat air as well as steam.

It is also to be noted that reversal of the direction of flow of steam through the fuel bed can be accomplished by opening the valves 12 and 9 and closing the valves 7 and 15. The resultant gas, by this arrangement, is discharged at the bottom of the generator and passes into the bottom of the superheater 3 as is the case if steam is introduced into the bottom of the fuel bed.

I have here shown boilers or super-heaters with vertical fire tubes but it is to be understood that I do not limit myself to this type of boiler as the principle of conserving the waste heat may be applied to boilers of any type, either fire tube or water tube and with horizontal or inclined as well as vertical tubes. While I have shown a single gas generator in connection with the boiler super-heater, the principles of the invention may be applied equally well to a series of shells such as generator, carbureter and super-heater of a carbureted water gas set, or the blue gas and hydrogen generators of a hydrogen gas machine.

From the foregoing description it becomes evident that the efficiency of the gas generating apparatus is secured principally through the use of peculiar constructed boilers and super-heaters 2 and 3, employing a "checker-work" in the fire chambers through which the heated gases may pass, which serves to absorb and conserve the heat of the gases in the production and super-heating of steam and the principal feature of the invention, therefore, consists in the construction of the super-heaters or waste heat boilers as well as in the gas generating set as a whole as set forth in the appended claims.

Having thus described my invention, what I claim and desire to secure by Letters Patent is—

1. Apparatus for the manufacture of combustible or other gases consisting of a generator and a boiler-superheater, means for producing combustion in the generator, a conduit at the top of the generator to the bottom of the boiler-superheater, a valve in the said conduit, a second conduit from the bottom of the generator to the bottom of the boiler-superheater, a valve in said conduit, a discharge conduit for the generator at the top thereof and at the bottom thereof, a valve in each of the said last named discharge conduits, and a steam conduit leading from the boiler of the boiler-superheater and discharging through the bottom thereof, and thence selectively to the top or bottom of the generator through the first and second named conduits of the generator.

2. Apparatus for the manufacture of combustible or other gases consisting of a generator and two steam producing boilers having heat retaining refractory material substantially as described, conduits leading from the bottom of each boiler structure, each being connected by branches to both the top and the bottom of the generator, closable valves in each of the branches, one boiler having a gas discharging conduit and the other boiler being provided with a steam conduit with which the steam chamber of the other boiler is connected, the steam conduit discharging to the generator through the conduits leading to the last named boiler.

3. Water-gas generating apparatus comprising the combination with a generator, of a boiler superheater for the production of steam by the gases of combustion, a second boiler in communication at the bottom with the generator, the steam space of the second boiler being connected with the steam space of the boiler of the boiler-superheater, a conduit for discharging steam from the boiler of the boiler-superheater through the fuel bed of the generator to the second boiler, and a discharge conduit for the generated gases passing through the second boiler.

4. Water-gas generating apparatus comprising the combination with a generator, of a boiler-superheater, a conduit leading from the generator to the boiler through which the gases of combustion may pass, a steam conduit from the boiler of the superheater discharging into the generator to pass entirely through the fuel bed thereof, a second boiler having heat absorbing refractory material for retaining and storing heat, a conduit connecting the same with the generator whereby the generated gas passing through the refractory material and second boiler may transmit its heat thereto, a discharge conduit for the cooled gases from the said second boiler, the steam space of the second boiler being connected with

the steam space of the boiler of the superheater.

5. A water-gas generating apparatus comprising a generator having a fuel bed, a boiler-superheater for the production of steam, and a second boiler also adapted to produce steam, a conduit connecting the top and bottom of the generator with both boiler-superheater and boiler, both having a fire chamber provided with heat absorbing refractory material therein, the gases of combustion during the blast of the generator being passed through the boiler-superheater to produce steam, means for discharging the steam through the refractory material to raise the temperature practically to the point of disassociation of its elements, a conduit for discharging the super-heated steam into the fuel bed, means for passing the resultant hot generated gas through the second boiler, the heat being utilized to produce steam and the steam of the second generator being connected with the steam chamber of the first generator, the refractory material serving to maintain the temperature of the boilers nearly uniform during the successive periods of gas and blast generating respectively.

6. Water-gas generating apparatus comprising the combination with a generator, of a boiler-superheater, comprising a boiler shell having a chamber at the bottom provided with heat absorbing and retaining material, the boiler shell extending about the chamber providing a water jacket for the superheater portion of the boiler-superheater, a conduit leading from the top and bottom of the generator to the bottom of the superheater chamber, and a steam conduit leading from the steam space of the boiler to the upper end of the superheater chamber to discharge through the bottom of the superheater chamber to the generator through the gas conduits.

In testimony whereof, I sign this specification.

FRANK D. MOSES.
